TENSIONED CONCRETE REINFORCEMENT

Filed Dec. 7, 1927

Henry Sorenson
INVENTOR

UNITED STATES PATENT OFFICE.

HENRY SORENSEN, OF SAN FRANCISCO, CALIFORNIA.

TENSIONED CONCRETE REINFORCEMENT.

Application filed December 7, 1927. Serial No. 238,341.

My invention consists in the method to strut beams, or girders, which are drawn inwardly in infilled structures, where reinforcements are tensioned and locked to the beams, or girders, prior to the pouring, or laying, of the fireproof infilling; and while my invention may be used in various parts of the building as well as in reinforced concrete structures designed for other purposes, 10 I have described it applied to fireproof floors.

In the drawings:—

Fig. 1 is a cut illustrating my invention, just prior to the tensioning of the reinforcements.

15 Fig. 2 is a cut illustrating my invention with the tensioned, and locked, reinforcements in place, all of which are embedded in concrete, or any other suitable infilling.

Fig. 3 illustrates a plan view of my invention, with the tensioned and locked reinforcements, in place and ready to receive the infilling.

Fig. 4 illustrates a strut, which may, however, be of any other suitable design.

20 Similar numerals designate similar parts, and numeral 1 designates the reinforcements. 2 is a hook at one end of the reinforcement 1. 3 designates the beams, or girders. 4 is a wedge-like member into which the other 25 end of reinforcement 1 is bent. 5 is the point of the wedge-like member 4. 6 is the flange of the one of beams 3. 7 are the columns which support beams 3. 8 is a strut. 9 are bolts. 10 are holes in the web 30 of beams 3. 11 are nuts which fit bolts 9. 35 12 designates the concrete or any other suitable infilling.

40 My invention may be applied to any known way, in which reinforcements are initially tensioned and locked to the beams, or girders, and I have, herein, described the said tensioning and locking of the reinforcements in the following manner.

45 As shown in Fig. 1, I hook ends 2, of reinforcements 1, to the flange of the one of the two opposed beams 3. Point 5, of the wedge-like member 4, of the other end of reinforcement 1, just clears flange 6 of the opposed beam 3, so that reinforcement 1 becomes tensioned, when the wedge-like member 4 is driven against flange 6 of beam 3. 50 After 4 is driven, point 5 is bent in, whereby reinforcement 1, while tensioned, becomes locked to the two opposed beams 3.

55 After having dealt with the above, I am

now coming to that which constitutes my invention, herein.

It will readily be understood, that the tensioning of a number of reinforcements 1, will increase the inwardly drawing force on 60 beams 3 with each added reinforcement 1; and that each additional, tensioned, reinforcement 1 will have the inclination to slacken the previously tensioned reinforcements 1, due to the tendency which beams 3 65 have to be drawn further inwards with each added reinforcement.

I, therefore, find it advisable to provide for means to adequately strut the beams 3 against the inward draw, which is caused 70 by the tensioning of reinforcements 1, and in the drawings I have illustrated the means, by which I strut beams 3, as follows:—

In Fig. 1 I have shown a cut of horizontally extending strut 8, which is firmly attached to the upper part of the inside web of beam 3, by means of bolt 9 and nut 11, through hole 10 in said web. Strut 8 is put in place, before the initial tensioning of reinforcements 1 takes place, prior to the infilling of concrete 12, and when infilling 12 is poured strut 8 becomes embedded in 12, as shown in Fig. 2. Fig. 2 illustrates a completed concrete floor, with the reinforcements 1, which were initially tensioned and 80 locked to beams 3, also embedded in concrete 12. Instead of using bolt 9 and nut 11, I may rivet 8 to the web of beam 3.

In Fig. 3 I have shown a plan view of the system ready to receive the concrete. 90 I prefer to attach strut 8 only to the outside beams, or girders,—but on their inside web,—for the reason that the draw, on each side of the inner beams 3, is equalized by the system of tensioned reinforcements 1 95 on both sides of the inside beams 3. In order to obtain this equal draw, I prefer to tension each row of the reinforcements 1, simultaneously, throughout the whole width, or length, of the building, with men 100 working, at the same time, at each section of beams 3.

In Fig. 4 I have shown a separate plan view of strut 8, as it is illustrated in Figures 1 and 2, and which consists of suitable 105 lengths of angle-irons riveted together, on a truss principle, to form a strut, which has the necessary stiffness to resist the inward draw on the beams 3, caused by the initial tensioning of the reinforcements 1. Strut 110

8 is attached to the web of beam 3, as hereinafore described.

I claim:

1. In an infilled structure with reinforcements connecting and initially tensioned and locked to opposed supports, means adapted to strut said supports against the draw caused by the initial tensioning of said reinforcements, said means remaining 10 embedded in the infilling of said structure.

2. In an infilled structure with reinforcements spanning and initially tensioned and locked to the flanges of opposed beams, the combination of struts adapted to protect said beams against the draw of said tension attached along the webs of the outside beams, said struts remaining embedded in the infilling of said structure. 15

HENRY SORENSEN.
